UNITED STATES PATENT OFFICE.

JACOB BENSING, OF MALINTA, OHIO.

RECEIVING-TABLE FOR BRICK OR TILE CUTTING MACHINES.

SPECIFICATION forming part of Letters Patent No. 718,078, dated January 13, 1903.

Application filed July 21, 1902. Serial No. 116,425. (No model.)

To all whom it may concern:

Be it known that I, JACOB BENSING, a citizen of the United States, residing at Malinta, in the county of Henry and State of Ohio, have 5 invented certain new and useful Improvements in Receiving-Tables for Brick or Tile Cutting Machines; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 My invention relates to improvements in receiving-tables adapted to be used in connection with machines employed in automatically cutting tile, brick, or other products from one or more columns of clay or other 20 plastic material as the same is continuously forced from the die of a mill, and especially designed to be used in connection with the machines described in United States Letters 25 Patent Nos. 411,638, 524,302, and 563,252, granted to me, respectively, September 24, 1889, August 14, 1894, and July 7, 1896, and it more particularly relates to improvements in the delivery device described in United States Letters Patent No. 621,815, granted to me 30 March 21, 1899.

The object of my improvements is to provide suitable and effective means for carrying the tile or brick away from the cutting-machine as they are received therefrom and 35 place them in separated position on pallets arranged in position to receive them and carry the same, with the brick thereon, forward to a point where they are removed to drier-cars or otherwise disposed of, all of which is hereinafter more specifically described and finally 40 claimed.

While the essential features of my invention are necessarily susceptible of modification, the preferred embodiment thereof is 45 illustrated in the accompanying drawings, in which—

Figure 1 is a vertical longitudinal sectional view of my improved delivery-table and pallet-carrier on the dotted line $x-x$ in Fig. 2. 50 Fig. 2 is a top plan view of the same. Fig. 3 is a vertical sectional view of my improved compensating gear. Fig. 4 is a transverse

sectional view of the same. Fig. 5 is a plan view of the links forming the endless pallet-carrier chain, and Fig. 6 is an end elevation 55 of the same.

Similar letters and numerals of reference indicate similar parts in all the figures of the drawings.

In carrying out my invention I employ a 60 delivery-table A, elevated in position at the forward end of the cutting-machine B to receive brick or tile therefrom, and the pallet-carrier C, arranged in subjacent position to said delivery-table A and having at its forward end a supporting-rack or delivery-frame 65 D. Proceeding to describe in detail these several parts and their adjuncts, 1 designates the usual longitudinal sills upon which the machines mentioned are mounted. Rising from 70 the sills 1 are the vertical legs or standards 2 of the pallet-carrier C, said standards supporting the sides 3, which are suitably connected and strengthened by the transverse bars 4. The sides 3 are provided with the endless inner track 5 and the outer track 6, running parallel with the upper and lower edges of the sides 3 and having conical bearing-surfaces between which is mounted an endless 75 pallet-carrier chain having a series of pivoted or loosely-connected sections. These pivotal sections comprise a pair of base-plates 7, provided with the single and double perforated bearing-lugs 8 and 9 to receive the spindles or pins 10, on which are mounted the anti-friction-rollers 11. The rollers 11 have conically-formed bearing-surfaces or peripheries to adapt them to fit the conical tracks 5 and 6 of the sides 3. It will be readily seen that 80 by providing conical bearing-surfaces on the tracks and rollers the carrier always seeks or tends to move toward the center of the table, the wear of the tracks being thus compensated for and the carrier caused to operate smoothly and with little friction. 90

Each pair of base-plates 7 is connected and held in rigid transverse relation to each other by a supporting-bar 12, being bolted thereto, suitable perforations being provided in the base-plates and bars for that purpose. The 95 plates 7 and the bars 12 are provided at their ends with rectangular perforations 13, so as to form endless racks when the sections are connected, with which suitable spur-gears,

hereinafter mentioned, mesh and furnish the required motive power for the pallet-carrier. The sections as thus constructed are connected in series to constitute the pallet-carrier by means of the pivotal bolts or spindles 10, which pass through the pairs of lugs 9 at one side of the base-plate and through the corresponding single lug 8 at the adjacent side of the next succeeding link or member and suitably secured therein. The carrier with the antifriction-rollers 11, which are mounted on the spindles 10, in position on the tracks 5 and 6, are shown in Fig. 1.

Journaled in the rearward portion of the sides 3 is the transverse shaft 14, on which are mounted the large spur-gear 15, which is connected by a chain to gearing, hereinafter more specifically referred to, and the smaller spur-gears 16, which are located between the sides 3 and the upper and lower portions of the inner track 5 and in alinement with the endless racks formed by the perforations 13 in the base-plates 7 and bars 12 of the carrier-links, with which the spurs of the wheels 16 mesh, thus making provision for power to run the endless carrier-chain.

To the rear of the tracks 5 and 6 and on the upper edges of the sides 3 is journaled the supporting roller or rung 17, which is for the purpose of forming a support for the rear of the pallets 18 as they are placed on the carrier-chain preparatory to being carried forward to a position to receive the brick or other deposits from the delivery-table A. Secured to the rear portion of one of the sides 3 are the vertical spindles 19 to receive the axially-perforated horizontally-disposed guide-wheels 20, which are slightly elevated above the horizontal plane of the endless pallet-carrier and adapted to act as guides and limit the transverse movement of the pallets 18 as they are placed on the carrier.

The superimposed delivery-table A is for the purpose of receiving the brick from the cutting-machine B and carrying them forward on a descending plane to a point where they are deposited on the pallets 18 as the same move forward, and comprises the sides 21, the thin sheet-metal plates 22 and 23, and the rungs or rollers 24 and 27, on which is mounted the endless belt or apron 25. The sides 21 have suitable lugs or seats formed on their inner surfaces, to which are securely bolted the plates 22 and 23 at the front and rear portions thereof, respectively. The sides 21 also have the enlarged and circularly-formed forward ends 21' to adapt them to rest on the upper surfaces of the sides 3 of the pallet-carrier table C and to support the forward end thereof a suitable distance above the pallet-carrier chain to escape the pallets 18 as they are moved forward on the carrier in position to receive the brick or tile as they leave the forward plate 22.

65 The plates 22 and 23 have their upper surfaces corrugated or provided with longitudinal depressions, as shown in Fig. 2, for the

purpose of decreasing the frictional surface of the plates and preventing the wet or damp surfaces of the brick as they move forward on the same from adhering and sticking thereto, as is the tendency when a smooth surface is used and which has heretofore much retarded the descending movement of the brick or tile. The rear edges of the plates 22 and 23 are concaved or depressed, so as to form laterally-disposed pockets or troughs 26, the ends of which are closed to adapt them to retain a lubricating fluid therein. The front edges of the plates 22 and 23 are preferably beveled on their under sides and are adapted to be so arranged in relation to each other as to have their beveled edges overlap the pockets 26 in such manner as to form a narrow slit or feed-passage between the forward and rearward edges of the adjacent plates, as shown in Figs. 1 and 2, to permit of an overflow of fluid passing from the pockets and over the surface of the plates. Any suitable means may be provided for supplying lubricating fluid to these pockets.

Journaled to the sides 21 of the delivery-table are the rungs or rollers 24 and the enlarged roller 27, all of which have their upper surfaces on a descending plane with those of the plates 22 and 23 and are adapted to carry and support the endless belt or apron 25. The shaft 28, which carries the roller 27, projects beyond one of the sides 21 and carries on its outer end the pulley 29. A belt 30 connects the pulley 29 with a pulley provided on the cutting-machine B, by means of which power is supplied to run the belt or apron 25. A roller 31 is journaled to the lower portion of the brackets 32 and is arranged in suspended position beneath one of the rollers 24 in close proximity to the large roller 27 and acts as an idler over which the under portion of the belt 25 passes. The tension of the belt 25 is regulated by means of the hand-screws 33, which extend through the upper transverse portions of the brackets 32 and bear against suitable lugs provided on the sides 21, thus adapting the idler 31 to be vertically adjusted and loosen or tighten the belt 25, as desired.

Rising from the sides 3 of the pallet-carrier table and adapted to act as supports for the superimposed delivery-table A are the standards 34. A brace 35 is provided on the forward standard 34, and, as will be noticed, its under surface is provided with the downwardly-extending web 36, which acts both as a strengthener for the brace 35 and as a feed-regulator for the pallets 18 as they move forward on the endless pallet-carrier chain. I so arrange the brace 35, having the downwardly-projecting web 36 thereon, with relation to the horizontal surface of the pallet-carrier as to provide only sufficient space to permit of one of the pallets 18 passing between the same at one time. Should it happen that more than one pallet is fed into the machine at one time or the end of one over-

laps the next preceding pallet, the forward end of the upper pallet will strike against the web 36 and be held until the preceding or under pallet has passed beyond the same and 5 will then fall in place behind the moving pallet and be carried forward in its turn to receive the brick as they drop from the forward end of the delivery-table A.

In the rear of each of the sides 3 of the 10 pallet-carrier table is provided the vertical elongated slots 37 to receive the bolts 38, passed through the lower perforated portion of the adjusting-standard 39, which extends upwardly therefrom and is pivotally connected to the rear of the sides 21 of the delivery-table. The lower portions of the standards 39 are also provided with the transverse segmental slots 40, adapted to receive bolts 41, which are also passed through the 15 vertical slots 37. The standards 39 are provided on one side with an outwardly-projecting apertured lug 42, the said aperture being internally screw-threaded to receive the adjusting or stop bolt 43, which bears 20 against the upper surfaces of the sides 3 of the pallet-carrier. It will be obvious that by loosening the nuts on the bolts 38 and 41 the delivery-table may be longitudinally or vertically adjusted and enable the rear plate 23 25 to be brought in close proximity to the endless chain of the cutting-machine in suitable position to receive the brick or tile therefrom.

I will now briefly describe the pallet-delivery frame D, which is pivotally secured to the upper forward portion of the sides 3 of the pallet-carrier table C. The construction of this frame is similar to that described in my Patent No. 621,315, above referred to, and 30 which is fully described therein. The object of employing this table is to provide suitable means for receiving the loaded pallets as they are passed from the endless pallet-carrier chain and to facilitate their being taken away 35 by hand to drier-cars or otherwise suitably disposed of. This frame consists of the sides 44, pivotally secured to the forward ends of the sides 3 of the pallet-carrier, and has suitable rungs or rollers mounted in a frame pivotally secured between said sides 44 and adjustable therein, over which the pallets move. 40

To impart motion to the transverse shaft 14 of the pallet-carrier table C and propel the endless carrier-chain, I employ suitable clutch 45 mechanism. The motion is preferably transmitted through a line-shaft 45, which is mounted longitudinally in suitable bearings 46, supported on transverse braces connecting the sills 1. The line-shaft 45 is provided 50 with a beveled gear 47, which meshes with and drives a companion beveled gear 48, mounted on a transverse counter-shaft 49, located in suitable bearings 50, on whose projecting end is provided a frictional clutch or 55 compensating mechanism, which is adapted to regulate the relative movement of the cutting-machine and pallet-carrier.

Any suitable construction of frictional gearing may be employed, and although I will proceed to describe one simple and effective form 70 of friction-clutch, yet I wish it to be understood that I do not limit my invention to any particular form of clutch or to its location, as I may vary the same at will.

Referring to Fig. 3, it will be seen that the 75 outer end of the shaft 49 is threaded, as indicated at 51. Over the outer end of the shaft 49 I slip the beveled gear 52, which is secured to the shaft by means of the binding-screw 53. I next slip upon the shaft the spur-gear 80 54, adapted to be loosely mounted thereon. Alternating with the spokes 55 and projecting through perforations in the rims and resting in suitable sockets provided in the hub of the spur-gear 54 are the pins or spindles 85 56, on which are loosely mounted the idler beveled gear-wheels 57, which are adapted to mesh with the beveled gear 52 and with the beveled gear 58, which I next slip loosely on the shaft 49 and retain in place thereon by 90 means of a collar 59, suitably secured to the shaft. The hub of the beveled gear 58, which is axially bored to receive the shaft 49, is enlarged and provided on its outer face with the annular V-shaped groove 60 to receive the annular conically-flanged portion 61 of the binding-collar 62. The inner surface of the collar 62 is provided with the elongated groove 63 for the reception of the feather 64, which is embedded in the shaft 100 49 and enables it to have a longitudinal movement thereon and prevents any rotary movement. It now remains, therefore, to provide a convenient and simple means for causing and maintaining a proper frictional engagement between the parts described. I therefore slip upon the shaft 49 the coiled expansion-spring 65, or, if preferable, a rubber collar, and beyond this a hand-wheel 66 is threaded on the end of the shaft. It will be 110 obvious that by rotating the wheel 66 in one direction the collar 62 will have its annular conical flange 61 forced into frictional contact with the surface of the V-shaped groove 60 in the hub of the beveled gear 58, which 115 is mounted loosely on the shaft and moves in the opposite direction to that of the friction-collar 62 by reason of the fact that the idlers 57 mesh with the rigid beveled gear 52 and cause a movement in the opposite direction on the 120 part of the beveled gear 58, thus retarding the movement of the spur-gear 54 and regulating the speed of the cutting-machine and pallet-carrier chains, which are operated by the same power, being connected by the 125 drive-chain 67, driven by and meshing with the compensating gear 54.

The endless pallet-carrier chain is geared to move slightly faster than the endless carrier-chain of the cutting-machine and the endless 130 apron 25 of the delivery-table A in order that the movement of the pallets may be slightly faster than the movement of the bricks on the delivery-table and therefore receive the

brick or other cut matter in separated position thereon, as shown in Fig. 1, ready to be removed to drier-cars or other suitable place without first having to separate them by hand. It is therefore obvious that much time and labor are saved by not having to separate the brick by hand as they are received from the cutting-machine and place them on the pallets preparatory to going to the drier and that the mutilating thereof necessarily incident to their being handled is entirely obviated.

It will of course be understood that I have merely shown and described preferred forms of construction of clutch mechanism, delivery-table, pallet-carrier table, and delivery-frame and that such mechanism and devices may be varied in their construction without departing from the spirit of my invention or sacrificing any of the numerous advantages apparent to those skilled in the use of this class of machinery.

Having described my invention, what I claim as new, and desire to secure by Letters Patent, is—

1. The combination with a brick and tile cutting machine having an endless cutting-belt, and a delivery-table arranged beyond and on a declining plane from said machine, of a carrier-table arranged beneath said delivery-table and having an endless carrier belt or chain thereon, pallets on said carrier belt or chain and adapted to be carried forward and beyond the delivery end of said delivery-table by said carrier belt or chain and receive cut matter from said delivery-table in separated position thereon, substantially as specified.

2. The combination with a brick and tile cutting machine having an endless cutting-belt, of a frame arranged adjacent to the discharge end thereof, tracks on said frame, an endless carrier-chain on said tracks, means for imparting motion to said chain, a delivery-table supported above said frame, said table having a forwardly-declining surface and its front end in close proximity to said chain, pallets on said chain and adapted to be carried forward and from under the forward end of said table by said chain in such manner as to receive deposits dropping from said table, substantially as specified.

3. The combination with a brick and tile cutting machine, and a table arranged beyond and below the same, of an endless carrier-chain on said table, a declining way leading from the delivery end of the cutting-machine to a point slightly above the horizontal surface of the carrier-chain, pallets or boards carried by said carrier-chain, said chain adapted to have a swifter movement than the cut matter as it is forced from said machine and down the said way and to cause the same to be received in separated position on the pallets as they move forward, substantially as specified.

4. The combination with a brick and tile cutting machine, a table arranged beyond and below the same, an endless carrier on said table and adapted to receive and carry pallets thereon, of opposite side bars adjustably supported above said table in inclined position and extending toward the cutting-machine, plates arranged on the front and rear portions of said bars, said plates having oil-pockets and overflow-passages between their adjacent edges and their upper surfaces corrugated, transverse rungs interposed in the space between said front and rear plates and connecting said bars, an endless apron on said rungs, means for tightening said apron, and means for imparting motion to said apron, substantially as specified.

5. The combination with a brick and tile cutting machine, a frame arranged beyond and below the same and a declining way leading from the delivery end of the cutting-machine to a point above said frame, of tracks on said frame, an endless carrier on said tracks, pallets supported and carried by said carrier, vertical spindles secured to the rear of said frame and projecting above the surface of said carrier, guide-wheels mounted on said spindles in slightly-elevated positions and adapted to limit the transverse movement of said pallets, means for imparting motion to said carrier and cause the pallets to consecutively move forward as they are placed thereon and receive the cut matter from said way in separated position.

6. The combination with a brick and tile cutting machine and a way declining from its discharge end, of a table arranged beyond and below the said way, an endless carrier on said table, pallets carried and supported by said carrier, a transverse strip between the said way and table and adapted to regulate the forward movement of said pallets and prevent more than one passing under the front end of the table at one time, and means provided for imparting motion to said carrier.

7. The combination with a brick and tile cutting machine having a table, carrying an endless chain, arranged beyond and below the same, and a way connecting the machine with the table, of a frame arranged on the front of said table and pivoted thereto, transverse rungs interposed within said frame and adapted to be vertically adjusted, substantially as specified.

8. The combination with a brick and tile cutting machine adapted to carry and cut a column of matter into sections, of a table arranged in line with said cutting-machine, an endless carrier-chain on said table, boards adapted to be fed onto said chain and carried forward thereby, a superimposed inclined frame supported by said table and adapted to connect with said cutting-machine and to form a way for said cut sections to pass from said machine to said table, the said boards adapted to have a swifter forward movement

than said cut sections as they pass along said frame and to receive the same in separated position thereon, substantially as specified.

9. The combination with a brick and tile cutting machine adapted to carry and cut a column of matter into sections, of a frame arranged in line therewith, an endless track on said frame, an endless carrier-chain on said track, said chain consisting of flexibly-connected sections, each comprising a pair of base-plates having antifriction-rollers thereon and a transverse bar connecting said plates, pallets adapted to be carried by said chain, means for regulating the feed of said pallets, a way connecting said cutting-machine and frame, and means for regulating the speed of said chain so that the cut sections, as they leave said way, will be received on said pallets in separated position.
10. The combination with a brick and tile cutting machine having an endless cutting-belt, of a table arranged beyond and below the same, an endless carrier on said table, pallets 18 carried by said carrier, guide-wheels 20 on said table, a way connecting said machine and table, said way supported at one end by the adjustable standards 39 and comprising the sides 21, the front and rear plates 22 and 23, the rungs 24 and the enlarged rung 27, the endless apron 25 on said rungs, and the adjusting-roller 31, the said apron 25 adapted to have a slower movement than the endless carrier on said table, thus causing the cut matter forced over the said way from said machine to drop onto the pallets 18 in separated position as the same move forward, substantially as specified.

11. The combination with a brick and tile cutting machine having an endless cutting-belt, a table connected with said machine by an inclined way, said table comprising opposite sides, endless tracks on said sides and an endless carrier-chain on said tracks, of a transverse shaft positively geared to said chain, a belt connecting said gearing with suitable gearing on said cutting-machine, means for conveying motion to said belt, said means consisting of a power-shaft having a spur-gear thereon to engage said belt, a friction-clutch arranged on the said power-shaft and adapted to regulate the movement of said

spur-gear, and means for causing a yielding contact between said clutch and gear, substantially as specified.

12. The combination with a brick and tile cutting machine having an endless cutting-belt, a table having an endless carrier-chain and connected to said cutting-machine by an inclined way, of a power-shaft, a compensating gear mounted on said shaft, said gear comprising a loosely-mounted spur-gear, idlers loosely mounted between the rim and hub of said spur-gear, beveled gears mounted on either side of said spur-gear and adapted to mesh with said idlers, one of said beveled gears loose on said shaft, a friction-collar longitudinally movable on said shaft and adapted to have a yielding engagement with said loosely-mounted beveled gear, and means for increasing or diminishing the friction between said members, said compensating gear having connection between said machine and table and adapted to impart motion to the endless belts on the same, substantially as specified.

13. The combination, with a brick and tile cutting machine, of a declining way leading from the delivery end of said machine, said way composed of opposite side bars, plates interposed between the front and rear portions of said bars, transverse rungs interposed in the space between said front and rear plates and connecting said bars, an endless apron on said rungs, means for tightening said apron and means for imparting motion to said apron.

14. The combination, with a brick and tile cutting machine and a way declining from its discharge end, of a table arranged beyond and below said way, an endless carrier on said table, boards carried and supported by said carrier, means provided to regulate the forward movement of said boards, and means provided for imparting the desired motion to said carrier.

In testimony whereof I have signed my name to this specification in the presence of two subscribing witnesses.

JACOB BENSING.
